UNITED STATES PATENT OFFICE

ROSS J. ELLSWORTH, OF WOODSTOCK, ILLINOIS, ASSIGNOR TO HOLMES DISAPPEARING BED COMPANY, OF WOODSTOCK, ILLINOIS, A CORPORATION OF ILLINOIS

BED MOUNTING

Application filed December 1, 1926. Serial No. 151,893.

This invention relates to bed mountings and is particularly designed for use in conjunction with what may be generally termed concealed beds of the pivoted type.

5 It has for its object the provision of a mounting between the pivot and the bed, whereby the bed may be moved laterally with respect to the pivot.

With the above and other objects in view, 10 as will be apparent, this invention consists in the construction, combination, and arrangement of parts all as hereinafter more fully described, claimed and illustrated in the accompanying drawings wherein:

15 Figure 1 is a front elevation of a bed mounted in accordance with the present invention illustrating the bed elevated.

Figure 2 is a side elevation of a bed mounted in accordance with the present 20 invention with the bed in its lowered or horizontal operative position.

Figure 3 is a vertical section taken along line 3—3 of Figure 2 to illustrate the mounting forming the subject matter of the present 25 invention.

Figure 4 is a horizontal section taken along line 4—4 of Figure 2 and illustrates the 30 cooperation between the head end of the bed and the doors of a dressing room or closet, both in its operative and concealed positions.

Figure 5 is a vertical section taken along line 5—5 of Fig. 3 to illustrate the details of construction of the mounting connecting the head end of the bed to the pivot.

35 Concealed beds have been and are now more generally used in buildings where it is desired to so dispose of the bed when not in use so that the room may be used for other purposes than as a bedroom. Usually this involves economy of space and for this reason the bed is frequently concealed in a room or extremely large closet which serves the double purpose of being a dressing room and a closet both for clothes and concealing the bed.

40 Where this arrangement is used a bathroom is frequently provided, opening into the dressing room. Therefore it is desirable and advantageous to so mount the bed with respect to the closet or dressing room that, when it is raised and positioned within the dress-

ing room or when it is lowered into the main room for sleeping purposes, free access may be had from the main room into and through the dressing room. Also, the mounting of the bed should be such that the opening into the dressing room from the main room may be completely closed irrespective of the position of the bed, at the same time permitting free access from the main room into the dressing room.

45 It is the object of the present invention to provide a pivoted mounting for a bed of such a character that when the bed is raised or elevated it may be swung about its pivotal mounting into and out of the dressing room or closet. A movement of the bed laterally with respect to the pivot is provided so that after the bed has been placed in the dressing room or after it has been placed in the main room it may be moved to leave part of the 50 aperture or portal between the rooms clear to permit unobstructed movement between the dressing room and the main room and the operation of a door to act as a closure for the clear portion of the portal between said 55 rooms.

60 Reference being had more particularly to the drawings, 10 designates the frame of a portal or doorway between the main room and the dressing room of an apartment. This portal or doorway is adapted to be closed by the doors 11 and 12. The door 12 is hinged to the frame 10 to swing relatively thereto, while the door 11 is secured to a vertical pivot 65 bar 14 mounted between the top of the frame 10 and the floor. The position of this bar is such that it is located centrally with respect to the width of the door 11. When the door 11 is swung with the bar 14 to occupy one 70 position, the bar 14 is within the dressing room while a reversal of the position of the door exposes the bar 14 to the main room.

75 By reference to Fig. 2 it will be observed that the pivots 15 of the bar 14 are located under the door 11 so that the swinging of the door about said pivots 15 actually moves the bar into and out of the dressing room. By so arranging the pivots 15, the door 11 is always coplanar with the door 12 when the latter is closed, irrespective of whether the bar 80

14 is located within the dressing room or in the main room.

The bed designated generally as B in Fig. 2 is carried and supported by the bar 14. The head end 16 of the bed is positioned adjacent and parallel to the rod 14 and somewhat above the floor. A pair of horns 17 are secured to the lower end of the head end 16 of the bed and pivotally support the bed between their terminals. Therefore the bed B may be swung to and from horizontal or operative position as disclosed in Fig. 2 from and to the vertical or inoperative position which it is shown as occupying in Fig. 1. When the bed B is positioned as disclosed in Fig. 1 it rests substantially parallel to the head end 16 and the bar 14.

In order to mount the bed B and head end 16 thereof, on the bar 14, a rectangular frame 18 is rigidly fixed to the bar 14 by the brackets 19 at a point adjacent the lower portion of the head end 16. The upper and lower sides of this frame 18 are provided at their ends with the relatively large projecting rollers 20, the edge of each roller 20 being provided with a groove 21 for the reception of rails carried by the head end 16 as will be herein-after more fully described. Thus it will be apparent that the frame 18 is rigidly secured to the bar 14 adjoining its lower end and has a pair of rollers 20 projecting above the ends of its upper side and a similar pair of rollers 20 projecting below the ends of its lower side. This frame 18 moves with, and as a part of, the bar 14 and door 11.

Secured to the head end 16 of the bed and to the lower portion thereof for cooperation with the rollers 20 are a pair of rails 22, U-shaped in cross-section and connected at their ends by the transverse pieces 23, thereby creating a second frame on the head end 16 of the bed. These rails 22 extend completely across the inner face of the head end 16 of the bed and are concealed by said head end for the reason that no portions thereof project beyond the limits or confines of the head end 16. Thus the only portion of the mounting mechanism which is exposed when the bed is in either raised or lowered position is the bar 14 which extends above the head end 16.

The rails 22 being respectively located above and below the sides of the frame 18, one side of each of the rails 22 may be engaged by the grooves 21 of the adjoining rollers 20 whereby the rails 22, together with the head end 16 which carries the bed B may slide on said rollers and move relatively to the frame 18, the bar 14 and door 11.

In practice, the bed B is raised to occupy a position substantially parallel to the head end 16 of the bed. When this is done the entire structure is supported by the bar 14 through the medium of the brackets 19, the frame 18 and rails 22 and may be swung with said bar 14 and door 11. It will be observed

by reference to Fig. 4 that the width of the bed and head end 16 thereof is considerably greater than that of the door 11 and nearly approximates the combined widths of the doors 11 and 12. Therefore when the rod 14 is located in the main room as illustrated in full lines in Figure 4, the bed B and head end 16 may be moved relative to the rod 14 and to the left in Fig. 4 until the bed B and head end 16 are entirely clear of the door 12. The bed may then be lowered to the position disclosed in Fig. 2 and the door 12 will be swung about its hinges whereby free access may be had into the dressing room to the rear of the doors 11 and 12. This permits the dressing room to be closed by the doors 11 and 12 when the bed is in use and yet permits unobstructed access to be had thereto.

When it is desired to return the bed to the dressing room it may be elevated so that it rests substantially parallel to the door 11 and bar 14 after which the door 12 may be opened and the bed moved relatively to the bar 14 to occupy the position illustrated in full lines in Fig. 4 and the entire mechanism swung about the pivots 15 to reverse the position of the door 11 as shown in Fig. 4 thereby positioning the bed within the dressing room and presenting the plain surface of the door 11 to the main room. The bed B and the head end 16 may then be moved relatively to the door 11 and the bar 14, i. e., to the left in Fig. 4, referring to the dotted line positions whereby the opening of the door 12 may again be cleared so that ready unobstructed access may be had into and out of the dressing room through said door 12 which may be closed if desired.

The present structure therefore provides a mounting for a bed whereby the bed may be moved relatively to its mounting, irrespective of whether the bed is located in the main room or in the dressing room, for the purpose of permitting free and easy access into and out of the dressing room. In other words, by the use of the present mounting in connection with a pivot bed the entire opening between the dressing room and the main room is not obstructed by the bed at any time, but a portion thereof may be kept clear. Furthermore, whether the bed is in or out of the dressing room, the portal between the rooms may be closed. At all times the entire mounting, with the exception of a portion of the bar 14, is completely concealed by the head end 16 no matter what lateral position the end occupies with respect to said bar.

What is claimed is:

The combination with a bed end, of a pivot bar therefor, a substantially rectangular frame secured medially of its length to said bar to project laterally upon each side thereof, grooved rollers mounted in said frame and projecting above its upper horizontal side and below its lower horizontal side and

a second relatively longer rectangular frame, including side rails, fixed to the bed end, said rails being disposed above and below the horizontal sides of said first frame and substantially parallel thereto, to be received in the grooves of the aforesaid rollers, whereby the second frame may move relatively to the first frame.

ROSS J. ELLSWORTH.
